SLIP COVER FOR KITCHEN CHAIR PADS

Morris Morgenstern, Brooklyn, N. Y.

Application May 4, 1939, Serial No. 271,643

3 Claims. (Cl. 155—182)

This invention relates to new and useful improvements in a slip cover for kitchen chair pads.

Still further the invention proposes the construction of a slip cover for kitchen chair pads comprising a top layer of cloth material and a bottom layer of cloth material secured together along their front and side edges to form a casing having its back edge open in a manner to permit a chair pad to be inserted therein.

Still further it is proposed to provide the bottom layer with an inwardly extending slit extending inwards from the rear edge thereof to permit said rear edge to be easily opened in a manner to permit the chair pad to be easily slipped therein.

Still further it is proposed to provide a means in the form of tie strings for closing said slit after the chair pad has been inserted into the casing, and still another means in the form of snap fasteners for closing the open back edge in a manner to completely encase the chair pad.

Still further it is proposed to fashion the casing in a manner to accommodate differently shaped pads and to conform somewhat to the contour of the seat of the chair.

Another object of the invention is the provision of tie strings attached to the back edge of the casing in a manner to be secured to the back of the chair for holding the casing in position upon the seat thereof.

Still further it is proposed to provide an adjustable means for securing the casing to the back of the chair in a manner to permit the casing to be held in various adjusted positions on the seat.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a kitchen chair having a slip cover for chair pads applied thereto.

Fig. 2 is a sectional view on the line 2—2 of Fig. 1.

Fig. 3 is an elevational view of the cover for the back of the chair.

Fig. 4 is a sectional view on the line 4—4 of Fig. 1.

Fig. 5 is a bottom plan view of the slip cover, per se.

Fig. 6 is an enlarged sectional view on the line 6—6 of Fig. 5.

Fig. 7 is a view similar to Fig. 5 but illustrating a modification of the invention.

Fig. 8 is a plan view of a chair having a slip cover constructed according to a modification of the invention.

Fig. 9 is an enlarged sectional view on the line 9—9 of Fig. 8.

Fig. 10 is a perspective view of a slip cover, illustrating a side closing arrangement.

Fig. 11 is a perspective bottom view of still further modified view of a chair pad slip cover.

The slip cover for kitchen chair pads, according to this invention, is adapted to be used in combination with a chair 10 having a seat portion 10^a supported upon a plurality of legs 10^b. The chair 10 is further provided with a back 10^c extending vertically upwards from the rear edge of the seat portion 10^a.

The slip cover 11 includes a top layer of cloth material 11^a and a bottom layer of cloth material 11^b between which a chair pad 12 is adapted to be engaged. Binding material 13 is mounted upon the edge portions of the top layer of cloth material and the bottom layer of cloth material along the front and side edges thereof and is securely maintained in position by means of stitches for forming a casing into which the chair pad 12 is adapted to be inserted.

The back edges of the top layer of material and bottom layer of material are free of each other for forming an opening through which the chair pad 12 is adapted to be passed. The free edges of the layers 11^a and 11^b at the back thereof are individually provided with binding material 13^a as shown in Fig. 6. The bottom layer 11^b is formed with an inwardly extending slit 11^{bb} extending from the back edge thereof and which has a portion of the binding material 13^a secured thereto to prevent the edges from unravelling. This slit 11^{bb} is provided for permitting the chair pad 12 to be easily engaged through the back open edge of the casing.

A means is provided for closing the slit 11^{bb}. This means comprises a tie string 16 secured to the material at each side of the slit 11^{bb} and which are adapted to be tied together for holding the slit 11^{bb} closed. A further means is provided for closing the open back edge of the casing for completely encasing the chair pad 12. This means comprises snap fastener elements 15 mounted on the adjacent faces of the free back edge portions of the layers 11^a and 11^b. Tie strings 16 are also attached to the back edge of

the casing for securing the casing to the back 10^c of the chair 10. These tie strings are adapted to be passed around certain rungs of the chair back 10^c and tied together for securely holding 5 the casing and chair pad 12 in position upon the seat 10^a of the chair.

A cover is provided for engagement upon the top of the chair back 10^c. This cover 17 is constructed of material similar to the material from 10 which the layers 11^a and 11^b are formed and consists of a front layer 17^a and a rear layer 17^b. These layers 17^a and 17^b are securely attached together along their top and side edges by means of a binding strip 18 which is secured in 15 position by means of stitches 19. The bottom edges of the layers 17^a and 17^b are free of each other and form a pocket for permitting the cover to be slipped upon the top of the chair back 10^c as shown in Figs. 1 and 2.

20 The operation of this form of the invention is as follows:

The top cover 17 is engaged upon the top of the chair back 10^c by passing the chair back into the cover through the open bottom edge thereof. The slip cover is adapted to have the chair pad 12 passed therein through the open back edge thereof, and the back edge is adapted to be closed by engaging the snap fastener 15. The slip cover and chair pad are then ready to 30 be engaged upon the seat 10^a of the chair by resting the same upon the face thereof. For securing the chair pad 12 in position upon the seat 10^a the tie strings are attached to the outside rungs of the chair back 10^c.

35 According to the modification of the invention shown in Fig. 7 the construction of the slip cover 11' for kitchen chair pads is similar to that previously described, except that the layers 11^a and 11^b are slightly different in contour for accommodating a differently shaped chair pad. In 40 other respects this form of the invention is similar to the previous form.

45 According to the modification of the invention shown in Figs. 8 and 9 the construction of the slip cover for kitchen chair pads is similar to that previously described, except for the provision of an adjustable means for holding the chair pad 12 in various fixed positions upon the seat 10^a of the chair 10. This means comprises 50 a pair of stiff members 20 of whale bone or other similar material. Each of the stiff members 20 is encased within a cloth covering 21. The bottom layer 11^b of the casing is formed with openings 22 at each of its rear corners into which one end 55 of each of the stiff members 20 is adapted to be passed.

60 The bottom face of the cover 21 of the stiff members 20 is provided with a plurality of snap fastener elements 23 which are adapted to be selectively engaged upon complementary snap fastener elements 24 mounted on the inside face 65 of the bottom layer 11^b. These complementary snap fastener elements permit the stiff members 20 to be extended from the back edge of the casing enclosing the chair pad 12. The tie strings 16' are securely attached to the outer ends of 70 the casing 21 enclosing the stiff members 20 and are adapted to be passed around the outside rungs of the chair back 10^c for attaching the casing and chair pad to the chair back. In

other respects this form of the invention is similar to the previous forms.

In Fig. 10, the chair pad slip cover 11 is shown with a side opening 25 which may be closed by suitable slide fasteners 26, buttons, snaps, or the like.

In Fig. 11, an under-turned flap 27 is shown to lie folded under the bottom side of the slip cover 11'.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A slip cover for kitchen chair pads, comprising a top layer of cloth material and a bottom layer of cloth material secured together along their front and side edges to form a casing having its back edge open, said bottom layer being formed with a slit extending inwards from the rear edge thereof, means for closing said slit, means for closing said open back edge, a pair of stiff members adjustably mounted on said casing and projecting from the rear edge thereof, and tie strings attached to the extended ends of said stiff members and engageable on the back of said chair for securing said casing in position thereon.

2. A slip cover for kitchen chair pads, comprising a top layer of cloth material and a bottom layer of cloth material secured together along their front and side edges to form a casing having its back edge open, said bottom layer being formed with a slit extending inwards from the rear edge thereof, means for closing said slit, means for closing said open back edge, a pair of stiff members adjustably mounted on said casing and projecting from the rear edge thereof, and tie strings attached to the extended ends of said stiff members and engageable on the back of said chair for securing said casing in position thereon, said stiff members being constructed of whale bone or other similar material and being enclosed with a casing of cloth material.

3. A slip cover for kitchen chair pads, comprising a top layer of cloth material and a bottom layer of cloth material secured together along their front and side edges to form a casing having its back edge open, said bottom layer being formed with a slit extending inwards from the rear edge thereof, means for closing said slit, means for closing said open back edge, a pair of stiff members adjustably mounted on said casing and projecting from the rear edge thereof, and tie strings attached to the extended ends of said stiff members and engageable on the back of said chair for securing said casing in position thereon, said stiff members being constructed of whale bone or other similar material and being enclosed with a casing of cloth material, and said tie strings being attached to said cloth material.
